UNITED STATES PATENT OFFICE.

HANS GRÜNEWALD, OF HANOVER, GERMANY.

MANUFACTURE OF FIREWORK ARTICLES.

No Drawing.

Application filed April 5, 1924. Serial No. 704,512.

To all whom it may concern:

Be it known that I, HANS GRÜNEWALD, a citizen of Germany, and a resident of 40 Glockseestrasse, in the city of Hanover, Germany, have invented certain new and useful Improvements in the Manufacture of Fire-work Articles, of which the following is a specification.

This invention relates to pyrotechnics or fire-work articles and among other important objects it is intended to generally improve and facilitate the course of manufacture of such articles, and to greatly increase the number and variety of mixtures and of the pyrotechnic, optical, esthetic and other effects produced. The invention devises means of obtaining entirely novel fire-work articles, such as Bengalic flames, lights, rockets, parlor fountains, sparklers, stars and broadly speaking, of all articles of the kind producing a pyrotechnic light or fire-work phenomenon. In accordance with the previous art firework articles, such as for instance Bengalic sticks or the like, were generally manufactured by dipping the wires or sticks or the like into the pasty or liquid composition, or the composition was introduced into shells or tubes, and by this means fire work articles of different description were produced by a judicious selection of the various compositions. With this method of working, however, the stuffing of the tubes or shells, the dipping of the sticks, wires, cords or the like necessitated a great amount of help and much time, and there was the further drawback that it was impossible to applying a plurality of compositions by dipping upon one and the same carrier, the stick, wire or the like, or to immerse any desired length of sticks or the like; nor could the tubes or shells be made of any suitable length desired.

These inconveniences are overcome according to my invention by means of which the operator is enabled to apply a plurality of compositions successively onto the sticks, wires, cords or the like, and for any length desired. By this means one is enabled to produce the most variegated pyrotechnic effects combined with the maximum of burning period which may be extended to any desired degree. In view of these and other objects I preferably proceed by shaping and drying pieces of fire work composition of any suitable size, providing them with perforations, and then slipping such pieces to

which any desired shape may be given, onto a wire, stick, piece of asbestos, an igniting cord or the like, such pieces of composition are preferably manufactured by machinery, and in this manner chains, rings, stars and any other suitable figures or configurations may be obtained, with the sticks, wires and cords or the like as carriers, and by the aggregation and combination of various different compositions the most wonderful, astonishing pyrotechnic effects of constantly changing kind and of practically unlimited burning period may be obtained. Thus for instance, it does not present any difficulties to mount a plurality of compositions upon the so-called Bengalic sticks, heretofore merely employed for the production of a light phenomenon, halo or the like, and to make such wood sticks or wires of any length desired. There is also the possibility of introducing other articles, such as Christmas articles, tree decoration, tinsel and the like between the individual pieces of composition, and to connect the pieces of composition by a special igniting cord, which is preferably wound around the carrying wire or the like. As a point of importance it should also be pointed out that, when the several pieces of composition may be bought, every customer is enabled to make his own combinations of pyrotechnic effects in the most simple manner and according to individual taste. A great saving of costs is also realized by my invention, as there is no further necessity of dipping the sticks or wires or of filling and stuffing the shells, casings or the like. The pieces of composition are produced and shaped automatically and may be automatically mounted upon the cord, the wood stick or wire. Then, the ingredients of the composition, and the aggregation of different kinds of compositions may be selected in such a manner as to dispense in many cases with the use of the highly dangerous potassium chlorate, inasmuch as this substance is not indispensable in the manufacture of the composition by machinery from dry ingredients, while with the pasty or liquid compositions the presence of potassium chlorate was necessary. Instead of but one a plurality of carriers may also be used. The invention is not restricted to the specific form of embodiment herein described, but is susceptible of being applied in various ways, and to be modified in accordance with particular requirements and

without deviating from the spirit of the invention, as pointed out in the claims hereunto appended.

I claim:

- 5 1. The method of producing fire work articles, which consists in spacedly disposing a plurality of dried pieces of pyrotechnic composition upon an elongated cord-like unexploding carrier, and shaping the carrier with said pieces to assume different configurations.
- 10 2. The method of producing fire work articles which consists in forming pyrotechnic composition into a plurality of perforated pieces of pyrotechnic material, and disposing said pieces upon an elongated carrier.
- 15 3. The method of producing fire work articles, which consists in shaping a plurality of dry perforated pieces from pyrotechnic composition, spacedly and displaceably assembling said pieces upon an elongated carrier, disposing non-pyrotechnic articles upon said carrier between the pyrotechnic pieces and conductingly connecting the latter.
- 20 4. The method of producing fire work articles, which consists in shaping a plurality of separate pieces of fire work composition, and heat-conductingly aggregating and mounting such pieces in a substantially dry condition upon a substantially cord-like carrier.
- 25 5. The method of producing fire work ar-

ticles, which consists in shaping a plurality of separate pieces of fire work compositions, mounting these pieces and other articles upon a substantially thin, elongated carrier, and connecting the pieces of fire work composition with each other by igniting means separate from the other articles.

6. As a new article of manufacture, a pyrotechnic article, comprising a plurality of perforated dry pieces of pyrotechnic composition, spacedly and displaceably disposed upon an elongated carrier.

7. As a new article of manufacture, a pyrotechnic article, comprising a plurality of perforated dry pieces of pyrotechnic composition, and of Christmas articles, spacedly and displaceably disposed upon an elongated carrier, and igniting means connecting the pieces of pyrotechnic composition, and mounted upon the carrier.

8. As a new article of manufacture, a pyrotechnic article, comprising a plurality of dry, hardened pieces of pyrotechnic composition, a non-exploding, non-conducting carrier, supporting said pieces in spaced relation to each other, additional unexploding articles disposed on said carrier, and igniting means mounted on the carrier and connecting the pieces of pyrotechnic material.

HANS GRÜNEWALD.
